Primary Examiner — T. Chase Nelson*Assistant Examiner* — Kathleen M Sims(74) *Attorney, Agent, or Firm* — Thorpe North & Western LLP(57) **CLAIM**

The ornamental design for a sock support, as shown and described.

DESCRIPTION

FIG. 1 is a perspective view of a sock support showing my new design.

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken line showing of a sock in FIGS. 1-7 is included for the purpose of showing environmental structure that forms no part of the claimed design.
